VACUUM CLEANER

Osmund Holm-Hansen, Fairfield, Conn., assignor of one-half to John N. Ledbetter, Jr., New York, N. Y.

Application January 18, 1952, Serial No. 267,150

11 Claims. (Cl. 183—37)

My invention relates to vacuum cleaners for domestic use that can easily be operated on electric current obtained from an ordinary light and power circuit.

An important object of this invention is to provide a vacuum cleaner which can easily be manipulated and moved about, and has a flexible conduit or hose so coupled to the body or casing that it can be advantageously and conveniently swung about to reach any point within range of the intake line of the cleaner.

Another object is to provide a connection between the hose and coupling that permits the hose to be readily attached and detached, but retains the hose securely when the cleaner is in use.

A further object is to provide a vacuum cleaner that can readily be moved about merely by pulling on the hose.

Other objects will appear in the following description, and a preferred embodiment of my invention is illustrated in the drawings. But this disclosure is explanatory only, and I may change the construction shown in minor respects without really altering the essential features incorporated therein.

On the drawings:

Figure 1 is a top plan of my improved vacuum cleaner, as it appears when the hose is detached.

Figure 2 is a longitudinal section thereof;

Figure 3 is a transverse section of the cap connecting the hose to the cleaner; and

Figure 4 is a detail in section in the plane of line 4—4 on Figure 3.

The cleaner has a housing or body 1 with a vertical partition 2 inside, dividing the interior into a pair of compartments. One of these contains a fan in a casing indicated at 3, and the other receives the dust collecting pouch or bag 4. The two compartments are in communication with each other through an opening 5 in the lower part of the partition 2. The motor for the fan is indicated at 6 and the fan casing and motor are both secured to a rubber mounting ring 7 having a flange 8, affixed to a shoulder 9 in the housing 1 by screws 10; and the lower end of the fan casing has an inlet opening 13. The housing 1 has an outlet opening 11 in its upper end, with deflectors 12 therein, and beside this opening the top of the housing has a large aperture 14 closed by a cover 15, with a hollow, open neck 16 to which the suction hose is attached. When the motor and fan are operating, air flows through the neck 16 into the housing 1 and bag 4, which retains the dust and dirt, and out by way of the opening 5 and discharge outlet 11.

The neck 16 has a ring nut 17 screwed therein. At the outer end the neck 16 has an inside flange 18 forming a shoulder that faces the nut 17. The cover 15 is secured to the end of a handle 19 affixed to the neck 16, and, inside, the neck carries a rotatable socket member 20, with an exterior ring or flange 21. The inclined surfaces 22 form on the flange 18 and another part a raceway groove; and the flange 21 has a matching groove 23, these grooves receiving anti-friction elements 24. Hence the socket 20 can turn freely in the cover 15. The socket has a section of reduced diameter to form an inside shoulder 25 and the cover 15 is surmounted by a round hollow cap 26 with a flat lower face having a hollow boss 27 projecting therefrom. This boss has a shoulder 28 at its junction with the cap 26 and on the end of the boss is a flange 29. Between the shoulder 28 and flange 29 are rings 30 of rubber or other yielding

2

material cemented or otherwise rigidly secured to the boss 27. These rings can be part of a rubber sleeve slipped on the boss 27.

When the cap 26 is attached to the neck 15, the boss 27 fits the socket member 20 snugly and its inner end is near to the shoulder 25. The rings 30 are of slightly enlarged diameter and are slanted upward when they enter the socket 20. The cap 26 is thus yieldably secured to the cover 15.

10 The cap 26 has a bore 31 opening through one side and extending through the hollow boss 27 for insertion of the metal ring or neck 32 on the end of the usual rubber hose 33, or for the end of a metal tube to which the hose is coupled. The hose will be of standard length, and adapted to be coupled to a nozzle and other fittings or accessories at its outer or intake end. The cap 26 carries a round pin 34, part of which is exposed by an opening 35 to the bore 31, and this part has a recess 36 of the same curvature as the bore 31. On one end of the plug is an arm 37. When the neck or band 33 is inserted into the bore 31 at the side of the casing 26, the pin or catch 34 is turned to present the recess 36 to the neck 33 to permit the sleeve or neck 32 to enter the bore 31. The neck 33 fits this recess. Then the plug is turned by the arm 37 and acts as a catch to bind against the ring or neck 33 and connect the hose securely to the cap 26.

A fixed bushing 38 surrounds the socket 20, and has an out-turned rim 39 that is gripped between the nut 17 and flange 18. See Figure 3. The bushing 38 is inclined within the rim to form one side of the raceway at the flange 18. Over this bushing is slipped a cylindrical ring or boss 40, having a bayonet slot 41 to engage a stud 42 on the bushing 38, and the boss 40 is thus detachably mounted on the bushing 38. The boss has prongs 43 and an outside flange 44. The neck of the bag 4 is slipped over the prongs and flange 44 and held on the boss 40 by a rubber ring or card 45. The boss 40 is made fast to an arm 46 attached to a ring 47 and provided with a knob 48. This arm is just under the cover 15 and by turning it when the cover is taken off the housing 1, the bag and boss 40 can be disengaged from the bushing 38, and the bag separated from the boss 40 and emptied.

45 A snap catch 49 of any suitable design on the housing 1 engages a projection 50 on the cover 15, to hold the cover on the housing 1. The handle 19 has at one end a loop or ring 51 that encircles the neck 16 and is made fast thereto by a binding screw 52, at the other end the handle has a round knob 53 that fits a recess 54 in the 50 top of the housing 1, and when the catch 49 is unfastened, the handle 19, cover 15 and bag 4 can be removed together.

The socket 20 has an outturned rim 55 at its upper end that overlaps the flange 18. Rollers 56 on the bottom 55 of the housing permit easy movement, and the motor is controlled by a switch 57 of any suitable type. The rotatable coupling and retaining pin for the hose is best shown in Figures 3 and 4. The sleeve 32 carries a fixed metal sleeve or ring 58 with an outside encircling groove 59. The pin 35 engages this groove and holds the ring 58 in the casing. But the neck 58 fits the bore 31 and the pin 34 engages the groove 59 loosely enough to allow the hose to rotate around the axis of the ring 58. On rotation of the pin to carry the recess 36 into the 65 groove and register with the aperture 35, the ring 58 and hose can be detached. The flange 18 preferably has a shoulder to seat the rim 55 of the socket 20.

The casing 26 can only be detached from the cover 15 by an upward pull to free the boss 29 from the member 20. The user can move the housing about by pulling on the hose, and can rotate the hose and ring 58. Thus the hose can be made to reach any point for cleaning it. A sleeve 60 on the hose fits against the casing 26. This handling is facilitated by the rollers 56, two 75 of which are wide apart under the bag, and two casters 64 close together under the fan casing 3.

The housing is made in two sections, one above the other, with a rubber gasket 61 between them. The two 80 sections have ribs 62, and are united by screws 63 in said ribs. The upper parts of the ribs engage the bag to

space it from the inside surface of the housing. The bag can be of cloth or paper.

The casters 64 are of the usual type and are pivoted to the housing 1 to swing each about a vertical axis. With the casters relatively close together and the wheels 56 farther apart, the housing 1 can easily be shifted about in any direction by a pull on the hose 33. The hose remains firmly attached for this purpose and can only be disconnected by a smart pull upward.

The shoulders 28 and 29 can be integral with the part 27 or rings secured thereto, and the rubber rings 30 are parts on the outside of a rubber sleeve 65, held between the shoulders 28 and 29.

Having described my invention, what I believe to be new is:

1. A cleaner having a housing, a bag therein, the housing having an outlet opening, a fan and motor in the housing between the bag and said opening, the bag being supported in the casing with its top open, a hollow cap on the casing above the bag, the cap having a bore therethrough, one end of the bore delivering to said bag, a hose having a sleeve inserted into the inlet end of said bore, said sleeve having an exterior encircling groove, and a pin in said cap entering said groove to secure the sleeve rotatably in said cap, said pin being rounded and extending across the sleeve with its central portion in said groove, said portion having a recess of the same curvature as the inside of said bore, the pin being rotatable to bring the recess into registry with the inside surface of the bore to permit insertion and removal of said sleeve.

2. A cleaner having a housing, a bag in said housing, a fan and motor in the housing, a cover in the top of the housing over the bag, a hollow cap on the cover having a hose coupled thereto, the cap having a bore delivering to said bag, the housing having an outlet opening for the fan beside the cover, a handle connected to the cover and means carried by the cover for supporting the bag, one end of the handle having a detachable connection with the housing, so that by lifting the handle the cover, cap and bag can be removed from the housing.

3. A cleaner having a housing, a bag therein, the housing having a discharge opening, a fan and motor between the bag and said opening, a cover on the housing beside said opening, a rotatable socket member in said cover, anti-friction means between said cover and said member, a hollow casing having a hose coupled thereto, and a boss fitting said socket member, a bushing fixed in the housing and surrounding said socket, the bag having a tubular member attached to the neck thereof, said bushing and said tubular member having detachable connection with each other.

4. A cleaner having a housing, a bag therein, the housing having a discharge opening, a fan and motor between the bag and said opening, a cover on the housing beside said opening, a rotatable socket member in said cover, anti-friction means between said cover and said member, a hollow casing having a hose coupled thereto, and a boss fitting said socket member, a bushing fixed in the housing and surrounding said socket, the bag having a tubular member attached to the neck thereof, said bushing and said tubular member having detachable connection with each other, said connection being formed by a bayonet slot in said tubular member and a stud in said bushing.

5. A cleaner having a housing, a bag therein, the housing having a discharge opening, a fan and motor between the bag and said opening, a cover on the housing beside said opening, a rotatable socket member in said cover, anti-friction means between said cover and said member, a hollow casing having a hose coupled thereto, and a boss fitting said socket member, a bushing fixed in the housing and surrounding said socket, the bag having a tubular member attached to the neck thereof, said bushing and said tubular member having detachable connection with each other, said tubular member having prongs extending into the bag, and an external flange, the bag receiving said flange and a binding element encircling the neck of the bag adjacent said flange.

6. A cleaner having a housing, a bag therein, the housing having a discharge opening, a fan and motor between the bag and said opening, a cover on the housing beside said opening, a rotatable socket member in

said cover, anti-friction means between said cover and said member, a hollow casing having a hose coupled thereto, and a boss fitting said socket member, a bushing fixed in the housing and surrounding said socket, the bag having a tubular member attached to the neck thereof, said bushing and said tubular member having detachable connection with each other, said tubular member having an arm attached thereto for manipulating said tubular member.

10 7. A cleaner having a housing, a bag therein, the housing having a discharge opening, a fan and motor between the bag and said opening, a cover over the bag adjacent said opening, the cover having an open neck, with an inside flange presenting a shoulder, a bushing having a rim engaging said shoulder, a nut in the cover securing the bushing to said shoulder, a rotatable socket member in said bushing, a tubular member in the bag detachably connected to the bushing, a hollow cap having a boss in said socket member and a hose coupled to said cap.

15 8. A cleaner having a housing, a bag therein, the housing having a discharge opening, a fan and motor between the bag and said opening, a cover over the bag adjacent said opening, the cover having an open neck, with an inside flange presenting a shoulder, a bushing having a rim engaging said shoulder, a nut in the cover securing the bushing to said shoulder, a rotatable socket member in said bushing, a tubular member in the bag detachably connected to the bushing, a hollow cap having a boss in said socket member and a hose coupled to said cap, the hose being rotatably connected to said cap.

20 9. A cleaner having a housing, a bag therein, the housing having a discharge opening, a fan and motor between the bag and said opening, a cover over the bag adjacent said opening, the cover having an open neck, with an inside flange presenting a shoulder, a bushing having a rim engaging said shoulder, a nut in the cover securing the bushing to said shoulder, a rotatable socket member in said bushing, a tubular member in the bag detachably connected to the bushing, a hollow cap having a boss in said socket member and a hose coupled to said cap, the hose being rotatably connected to said cap.

25 10. A cleaner having a housing with an inlet opening, a dust collecting bag in said housing with its mouth adjacent said opening, a hollow cap mounted on the housing and having a part extending into said opening, a member surrounding said part, and anti-friction elements between said member and said housing within said opening, a hose rotatably connected to the outer end of the cap, the housing also having an outlet opening, and a fan and motor in the housing between the back and said outlet opening.

30 11. A cleaner having a housing with an inlet opening, a cap having a boss projecting into said opening, a ring surrounding said boss and having a raceway in its outer face, said housing having parts within said opening surrounding said ring and forming a cooperating raceway, and anti-friction elements in said raceways between said ring and said parts, a bag in the housing with its mouth adjacent said opening, the housing having a discharge opening, and a motor and fan between the bag and said discharge opening.

35 12. A cleaner having a housing with an inlet opening, a cap having a boss projecting into said opening, a ring surrounding said boss and having a raceway in its outer face, said housing having parts within said opening surrounding said ring and forming a cooperating raceway, and anti-friction elements in said raceways between said ring and said parts, a bag in the housing with its mouth adjacent said opening, the housing having a discharge opening, and a motor and fan between the bag and said discharge opening.

40 13. A cleaner having a housing with an inlet opening, a cap having a boss projecting into said opening, a ring surrounding said boss and having a raceway in its outer face, said housing having parts within said opening surrounding said ring and forming a cooperating raceway, and anti-friction elements in said raceways between said ring and said parts, a bag in the housing with its mouth adjacent said opening, the housing having a discharge opening, and a motor and fan between the bag and said discharge opening.

45 14. A cleaner having a housing with an inlet opening, a cap having a boss projecting into said opening, a ring surrounding said boss and having a raceway in its outer face, said housing having parts within said opening surrounding said ring and forming a cooperating raceway, and anti-friction elements in said raceways between said ring and said parts, a bag in the housing with its mouth adjacent said opening, the housing having a discharge opening, and a motor and fan between the bag and said discharge opening.

50 15. A cleaner having a housing with an inlet opening, a cap having a boss projecting into said opening, a ring surrounding said boss and having a raceway in its outer face, said housing having parts within said opening surrounding said ring and forming a cooperating raceway, and anti-friction elements in said raceways between said ring and said parts, a bag in the housing with its mouth adjacent said opening, the housing having a discharge opening, and a motor and fan between the bag and said discharge opening.

55 16. A cleaner having a housing with an inlet opening, a cap having a boss projecting into said opening, a ring surrounding said boss and having a raceway in its outer face, said housing having parts within said opening surrounding said ring and forming a cooperating raceway, and anti-friction elements in said raceways between said ring and said parts, a bag in the housing with its mouth adjacent said opening, the housing having a discharge opening, and a motor and fan between the bag and said discharge opening.

60 17. A cleaner having a housing with an inlet opening, a cap having a boss projecting into said opening, a ring surrounding said boss and having a raceway in its outer face, said housing having parts within said opening surrounding said ring and forming a cooperating raceway, and anti-friction elements in said raceways between said ring and said parts, a bag in the housing with its mouth adjacent said opening, the housing having a discharge opening, and a motor and fan between the bag and said discharge opening.

65 18. A cleaner having a housing with an inlet opening, a cap having a boss projecting into said opening, a ring surrounding said boss and having a raceway in its outer face, said housing having parts within said opening surrounding said ring and forming a cooperating raceway, and anti-friction elements in said raceways between said ring and said parts, a bag in the housing with its mouth adjacent said opening, the housing having a discharge opening, and a motor and fan between the bag and said discharge opening.
